TOGGLE TRIGGER MECHANISM

Earl L. Hardgrave, Midland, Tex.

Application February 20, 1953, Serial No. 337,911

9 Claims. (Cl. 42—69)

This invention relates to a novel trigger mechanism for a bolt action rifle and more particularly to a trigger mechanism provided with a novel set unit whereby the trigger may be easily set to release the sear after only a slight movement of the trigger and which set unit automatically disengages when the trigger is pulled or moved to a sear releasing position allowing the trigger to return to a full single stage with a maximum contact between the engaging surfaces of the sear and trigger and from which position the trigger may thereafter be again pulled either from said full single stage position or, by a simple operation of the set unit, from a set position.

Another object of the invention is to provide a trigger mechanism wherein the tension of an adjustable tension spring will maintain the set unit in an operative position until tension on the spring is released by a pull exerted on the trigger and whereupon the set unit will automatically move to a released or inoperative position to permit return of the trigger to a full single stage with maximum contact with the sear after release of the sear.

A further object of the invention is to provide a trigger mechanism having a toggle joint type unit forming the set unit thereof and which may be readily adjusted for varying the extent of pull required to move the trigger to a sear releasing position from a set position.

Another object of the invention is to provide a trigger mechanism having a novel construction of housing and frame whereby a portion of the mechanism may be economically constructed from sheet metal.

Various other objects and advantages of the invention will hereinafter become more fully apparent from the following description of the drawings, illustrating a presently preferred embodiment thereof, and wherein:

Figure 1 is a vertical sectional view, partly in side elevation showing a trigger mechanism mounted on the receiver portion of a bolt action rifle and with the trigger in a full single stage position and having maximum contact with a sear;

Figure 2 is a view similar to Figure 1 showing the sear in a released position;

Figure 3 is a top plan view of the trigger mechanism removed from the receiver;

Figure 4 is an enlarged transverse sectional view of the trigger mechanism taken substantially along a plane as indicated by the line 4—4 of Figure 1;

Figure 5 is an enlarged longitudinal sectional view of the trigger mechanism taken substantially along a plane as indicated by the line 5—5 of Figure 1;

Figure 6 is a fragmentary vertical sectional view taken substantially along a plane as indicated by the line 6—6 of Figure 5, and

Figure 7 is a fragmentary side elevational view of a portion of the trigger mechanism.

Referring more specifically to the drawings, for the purpose of more clearly illustrating the application and use of the novel trigger mechanism, designated generally 10 and comprising the invention, a portion of the receiver 11 of a bolt action rifle is illustrated in Figures 1 and 2

including a portion of the rifle bolt 12 having a sear engaging lug 13 depending downwardly therefrom.

The trigger mechanism 10 includes a housing, designated generally 14 which is formed from a folded and cut strip of sheet metal having spaced substantially parallel sides 15, as best illustrated in Figure 3, which are connected by spaced rivets 16, 17 and 18. The strip forming the housing 14 includes a downwardly depressed transverse portion 19 extending between and formed integral with complementary portions of the upper edges of the sides 15 and which is provided at its rear end with a depending extension 20 the lower end 21 of which is bent forwardly around the rivet or fastening 17. The sides 15, forwardly of the part 19, are provided with corresponding upwardly extending portions 22 having aligned apertures for receiving a pivot pin 23 by which the housing 14 is pivotally connected to the receiver 11, near the forward end of said housing. The side walls 15 at their forward ends are provided with inturned portions forming a front wall 24 and at their bottoms are provided with inturned extensions, adjacent the front wall 24, forming a bottom portion 25, which combines with said front wall 24 to form a pocket at the forward end of the housing 14 in which is seated the lower end of a compression spring 26, the upper end of which is seated in a downwardly opening socket 27 of the receiver 11, for urging the housing 14 to rock about the pivot 23 to maintain the rear portion of the housing in a raised position against the receiver.

30 A trigger 28 has an upper portion 29 which extends upwardly into the housing 14 between its sides 15, behind the strip 20. A pivot pin 30 extends through the trigger portion 29 and is supported in the sides 15 behind the lower strip portion 21 for swingably mounting the trigger 28 for forward and rearward swinging movement of the upper and lower ends thereof. The lower end 31 of the trigger 28 forms a finger engaging portion of conventional configuration.

A frame 32, which is formed from a single strip of sheet metal folded back upon itself intermediate of its ends, has portions thereof located adjacent its terminals 33 which straddle an intermediate portion 34 of the trigger 31 and which are secured thereto by suitable fastenings such as the rivets 35. The intermediate portion of the strip forming the frame 32 defines a transverse end wall 36 which is spaced from the trigger portion 34. A rivet 37 extends across the frame 32 and is supported thereby between the trigger portion 34 and end wall 36. A spring seat 38 is formed by substantially U-shaped strips having leg portions of different lengths the terminals of which are turned outwardly and back upon themselves to form hooks 39. The spring seat 38 is disposed in the frame 32 between its end wall 36 and the rivet 37 and the hook 39 of the longer leg thereof engages over the upper edge of the end wall 36 while the hook 39 of the shorter leg engages over the rivet 37, to support the spring seat 38 in an upwardly opening position in the frame 32. The intermediate or right portion of the spring seat 38, constituting the bottom thereof, is provided with a threaded opening 40 to adjustably receive a screw 41 which extends threadedly therethrough and which has a head 42 at its upper end disposed within the spring seat 38 forming an adjustable perch or spring stop. A jamb nut 43 threadedly engages the lower portion of the screw 41 and bears against the underside of the spring seat bottom to retain the spring stop 42 in different adjusted positions.

70 A sear 44 is turnably mounted in the upper rear part of the housing 14 on a pivot pin 45 which is supported by the sides 15. The sear 44 is shown in its normal position in Figure 1 and as thus disposed has an upwardly extending rearwardly facing shoulder 46 which engages

the forward face of the lug 13 to retain the firing mechanism, associated with the bolt 12, in a retracted cocked position. As thus disposed, the sear has a downwardly facing shoulder 47 at the rear thereof which engages against the rear rivet 18 to prevent the sear from rotating clockwise beyond its position of Figure 1. Forwardly of the pivot 45, the sear 44 is provided with a concavely rounded downwardly and rearwardly opening notch 48, and forwardly of said notch 48 and thereabove, the sear 44 is provided with a downwardly facing shoulder or surface 49 which extends to the forwardmost extremity of the sear.

The housing sides 15 adjacent their rear ends and bottoms are cut and bent inwardly and the inturned portions are notched to cooperate and form an apertured spring abutment 50, as best seen in Figure 4, which is disposed above the spring seat 38. An apertured spring guide 51 is held seated against the underside of the abutment 50 by the upper end of a main expansion coil spring 52, which extends downwardly into the spring seat 38 and which is supported at its lower end on the adjustable spring stop 42. A smaller inner expansion coil spring 53 has its lower end bearing on the spring stop 42 and extends upwardly therefrom through the aligned apertures of the spring guide 51 and abutment 50. A rigid rod 54 is disposed in the upper portion of the spring 53 and likewise extends through the parts 50 and 51. The rod 54 has a crossbar 55 at its upper end against which the upper end of the spring 53 bears to maintain the crossbar 55 seated in the notch 48 of the sear 44, so that said sear is normally turned clockwise by the tension of the spring 53 to its position of Figure 1 from its position of Figure 2.

A block 56 has a restricted inner end 57 which fits between the terminals 33 of the frame 32 and is secured thereto by a fastening 58, as best seen in Figures 5 and 6. A pin 59 seats in opposed recesses 60 formed in the abutting faces of the trigger portion 34 and block 56 to cooperate with the fastening 58 to maintain the block 56 rigidly relatively to the frame 32. The outer portion of the block 56 has a threaded bore 61 extending from top to bottom therethrough. The block 56 is split as seen at 62 from its outer end inwardly to the threaded bore 61 so that said bore can be expanded when a socket member 63 is threaded upwardly into the bore 61 whereby said socket member 63 will be frictionally gripped and maintained in an adjusted position in the block 56. The socket member 63 has an upwardly opening socket 64 provided with a flared upper end 65.

The adjustable socket member 63 constitutes a part of the toggle joint set unit, designated generally 66, which includes a lever, designated generally 67, having spaced substantially parallel sections 68, the lower portions of which straddle the block 56 and/or the frame terminals 33, as best illustrated in Figure 5. The lower ends of said sections 68 are connected by a crosspiece 69, as seen in Figure 6, which is disposed below the block 56 and to the underside of which is secured a thumb piece 70 having a roughened outer surface. The upper portions of the lever sections 68 are loosely disposed in the bottom part of the housing 14 beneath and spaced from the part 21 and are pivotally mounted therein on a pivot pin 71 which is supported by the sides 15. A spring 72 has a part thereof coiled about the pivot 71 between the lever sections 68 and is provided with an upwardly extending intermediate portion 73 which bears against the forward end of the abutment 21, which provides a fixed perch for the spring 72. The terminals 74 of the spring 72 are bent outwardly and around the forward edges of the lever sections 68, below the pivot 71, for urging the lever 67 to swing counterclockwise or rearwardly, as seen in Figures 1 and 2, about its pivot 71. The toggle joint 66 also includes a pin 75 forming a second lever thereof, the enlarged upper end of which is loosely disposed between intermediate portions of the

lever sections 68 and swingably connected thereto by trunnions 76. The restricted lower end of the lever pin 75 terminates in a tapered free end 77 which seats for fulcruming movement in the socket 64 including the beveled upper end 65 thereof. Thus, the socket 64, 65 and the tapered lever end 77 constitute the bottom pivot of the toggle joint 66, the pivot 71 constituting the top pivot thereof, and the trunnions 76 which pivotally connect the upper portion of the lever pin 75 to the intermediate portion of the lever 67 form the intermediate pivot of the toggle joint.

The upper ends of the lever sections 68 are beveled to form terminal portions 78 which are swingable into engagement with the abutment 21 to limit clockwise swinging movement of the lever 67 to but not beyond its dotted line position of Figure 1.

Corresponding ends of the shafts or pivots 30 and 45 are grooved as seen at 79 to receive the notched ends of a spring latch strip 80 which bears against the outer surface of one of the sides 15 for detachably retaining said shafts 30 and 45 in applied positions in the housing 14. A slotted latch strip 81 similarly engages a groove 82 of the pivot pin 71, for the same purpose.

The toggle joint set 66 is illustrated in an inoperative or broken position in Figure 1 and with the intermediate pivot 76 thereof disposed to the right of the top and bottom pivots. When thus disposed, the upper end of the upper trigger portion 29, which forms a sear engaging part or surface 83, fully seats against the sear shoulder 49 from its inner to its outer end in a full single stage position of the trigger mechanism where maximum contact exists between the trigger portion 83 and sear notch 49, so that maximum swinging movement of the trigger 28 in a counterclockwise direction about its pivot 30 from its position of Figure 1 toward its position of Figure 2 is necessary before the trigger portion 83 releases the sear. When release of the sear occurs, the sear 44 will be swung counterclockwise to its position of Figure 2 by the forward thrust on the lug 13 which is provided by the firing mechanism of which said lug forms a part. The main spring 52 resists this swinging movement of the trigger 28 to a sear releasing position and the trigger pull may obviously be varied by adjustment of the spring seat 42. The weak spring 53 is compressed when the sear 44 is released and swung counterclockwise to its position of Figure 2 and the bar 55 rides in the notch 48 as the spring 53 and guide rod 54 are displaced downwardly through the parts 50 and 51. Thereafter, when the lug 13 has again been moved rearwardly the weak spring 53 will expand turning the sear 44 clockwise back to its position of Figure 1 and so that the stronger spring 52 may thereafter swing the trigger 28 clockwise to re-engage the surface 83 fully beneath the sear shoulder 49 in its full single stage, full line position of Figure 1.

If it is desired to position the trigger 28 in a set position so only a slight pull or movement thereof will be required to release the sear 44, the thumb piece 70 is engaged to swing the toggle lever 67 clockwise about its pivot 71 from its full line to its dotted line position of Figure 1. This movement causes the intermediate pivot 76 to move from right to left across the dead center of the top and bottom pivots of the toggle joint and results in the toggle joint assuming an extended operative position. In this extended dotted line position of the toggle joint, the distance between the end pivots thereof is increased and as the upper pivot 71 is stationary, the lower pivot 65, 77 is displaced downwardly so that the trigger 28 and frame 32 are rocked counterclockwise about the trigger pivot 30 and the main spring 52 is additionally compressed. Accordingly, the trigger 28 is displaced to its dotted line position of Figure 1 in which set position only a small portion of the trigger end 83 engages the outer end of the sear shoulder 49. The tensioned main spring 52 exerts an upward thrust on the bottom pivot of the toggle joint and said spring is of sufficient strength to over-

come the tension of the spring 72 to thus prevent the intermediate pivot 76 from moving from left to right back across the dead center of the top and bottom toggle joint pivots, to thus maintain the trigger 28 in its set, dotted line position of Figure 1. When the trigger portion 31 is engaged and a rearward pressure exerted thereon initial rear movement of the trigger, counterclockwise about its pivot 30, will release the upward pressure on the bottom pivot of the toggle joint allowing the spring 72 to snap the middle toggle pivot 76 from left to right across the top and bottom toggle pivots to thus swing the lever 67 back to its full line position for breaking the toggle joint to render the set 66 inoperative. This will usually occur before the trigger end 83 disengages the sear shoulder 49. Accordingly, when the trigger thereafter re-engages the sear it will assume a full single stage position with maximum contact between the parts 83 and 49, as shown in full lines of Figure 1, and the lever 67 will again have to be swung manually clockwise from right to left about its pivot 71 to return the trigger mechanism to a set position where a slight trigger movement will be sufficient to release the sear.

Various modifications and changes are contemplated and may obviously be resorted to, without departing from the spirit or scope of the invention as hereinafter defined by the appended claims.

I claim as my invention:

1. A trigger mechanism of the character described comprising a housing, a sear pivoted to said housing, said sear having a shoulder spaced from the sear pivot, a trigger pivoted to the housing having a sear engaging portion spaced from the trigger pivot and engaging the shoulder of the sear for holding the sear in an operative firing mechanism cocking position, a main spring engaging said housing and trigger and urging said sear engaging trigger portion into full engagement with the sear shoulder, and a toggle joint set including a first lever and a second lever, said first lever having one end pivoted to the housing, said second lever having one end pivoted on a part of the trigger, the other end of said second lever being pivotally connected to an intermediate portion of the first lever and constituting an intermediate pivot of the toggle joint levers, said intermediate pivot being movable in one direction across a line extending between said end pivot of the first toggle joint lever and the first mentioned pivot of the second toggle joint lever from a broken to an extended operative position of the toggle joint set for rocking the trigger on its pivot against said main spring for moving the trigger toward a released position and for moving the sear engaging trigger portion into a position in partial contact with said sear shoulder.

2. A trigger mechanism as in claim 1, and abutment means limiting swinging movement of the toggle joint set toward an extended, operative position.

3. A trigger mechanism as in claim 1, and a toggle joint spring carried by said toggle joint and urging the toggle joint to a broken position whereby movement of the trigger to a sear releasing position will relieve the

pressure on the extended toggle joint to permit said toggle joint spring to move said toggle joint to a broken, inoperative position, said toggle joint spring being weaker than said main spring.

5. A trigger mechanism as in claim 1, the first lever of the toggle joint having an extension projecting below said intermediate pivot and forming an actuating lever for manual movement of the toggle joint to and from extended and broken positions.

10. 5. A trigger mechanism as in claim 1, and means adjustably locating the first mentioned pivot of said second toggle joint lever for varying the spacing between the toggle joint end pivots to adjust the extent of partial contact of said sear engaging trigger portion with the sear shoulder when the toggle joint is in an extended position.

15. 6. A trigger mechanism as in claim 1, said trigger having a frame forming a part thereof including a rearwardly extending portion, the trigger pivot being disposed between said frame and the sear engaging trigger portion, and one end of said main spring bearing on said rear frame portion.

20. 7. A trigger mechanism as in claim 1, said frame including a forward portion extending forwardly from the trigger, an adjustable fulcrum seat mounted in said forward frame portion for adjustment toward and away from said end pivot of the first toggle joint lever and forming a seat constituting a part of the first mentioned pivot of the second lever of the toggle joint.

25. 8. A trigger mechanism as in claim 7, said housing having an apertured seat for said main spring, a sear spring having one end disposed in said main spring and seated therewith against the frame and having an opposite end extending through the spring seat of the housing and toward the sear, a rigid guide stem disposed in said last mentioned sear spring end and having an outer end defining a head against which the last mentioned end of the sear spring engages, and said sear having a concavely rounded recessed portion against which the stem

30. 40. head slidably bears, said recessed sear portion being disposed between the sear shoulder and the sear pivot, and said sear spring being compressed by movement of the sear to a firing mechanism releasing position and reacting to return the sear to a cocked firing mechanism engaging position and to return the sear shoulder to a trigger engaging position.

35. 45. 9. A trigger mechanism as in claim 1, said housing being formed from a folded piece of sheet metal defining spaced side walls between which portions the sear and trigger are pivotally mounted, said housing having an open top through which a portion of the sear extends and an open bottom from which a portion of the trigger depends.
